UNITED STATES PATENT OFFICE

WALTER BUNZL, OF NEW YORK, N. Y.

DESIGN FOR A THERAPEUTIC LAMP

Application filed October 14, 1931. Serial No. 41,389. Term of patent 7 years.

To all whom it may concern:

Be it known that I, WALTER BUNZL, a citizen of the United States, residing at New York, in the county of New York and State of New York, have invented a new, original, and ornamental Design for Therapeutic Lamps, of which the following is a specification, reference being had to the accompanying drawings, forming part thereof.

I claim:

The ornamental design for a therapeutic lamp as shown.

WALTER BUNZL.
